US0D1064932S

(12) **United States Design Patent** (10) Patent No.: **US D1,064,932 S**
(45) Date of Patent: ** Mar. 4, 2025

(54) **BICYCLE FRAME**

(71) Applicant: **Specialized Bicycle Components, Inc.**,
Morgan Hill, CA (US)

(72) Inventors: **Sébastien Robert Jacques Joseph Servet**, Wolfgangzen (FR); **Tero Jakku**, Bonstetten (CH); **Peter Joachim Axel Denk**, Freiburg im Breisgau (DE)

(73) Assignee: **Specialized Bicycle Components, Inc.**,
Morgan Hill, CA (US)

(**) Term: **15 Years**

(21) Appl. No.: **29/874,505**

(22) Filed: **Apr. 20, 2023**

(51) LOC (15) Cl. **12-11**

(52) U.S. Cl.

(57) **CLAIM**

The ornamental design for a bicycle frame as shown and described.

DESCRIPTION

FIG. 1 is a top, rear and right side perspective view of a bicycle frame embodying the design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines in the drawings illustrate portions of the bicycle frame that form no part of the claimed design.

1 Claim, 7 Drawing Sheets
